Application filed March 17, 1898. Serial No. 674,281. Term of patent 3½ years.

To all whom it may concern:

Be it known that we, ALBERT GERSTENDORFER and MAX GERSTENDORFER, citizens of the United States, and residents of the borough 5 of Manhattan, in the city, county, and State of New York, have invented and produced a new and original Design for an Advertising-Column, of which the following is a specification.

The leading feature of our design is an advertising-column substantially as shown in the accompanying drawing.

In the drawing, *a* represents the base of the design, from which a pillar *b* rises. This pil-
